UNITED STATES PATENT OFFICE.

GARLAND H. ROOSE, OF CHICAGO, ILLINOIS.

INTERNAL-COMBUSTION ENGINE.

Application filed January 28, 1927. Serial No. 164,283.

My invention relates to improvements in internal combustion engines, and it consists in the combinations, constructions, and arrangements herein described and claimed.

5 An object of my invention is to provide an internal combustion engine in which each cylinder has a single port and a novel means for automatically connecting the single port of each cylinder successively with the intake and exhaust.

10 A further object of my invention is to provide a device of the type described which prevents loss of compression.

15 A further object of my invention is to provide a device of the type described which is relatively noiseless in operation.

20 A further object of my invention is to provide a device of the type described which has novel means for automatically adjusting parts for taking up wear.

25 Other objects and advantages will appear in the following specification, and the novel features of the invention will be particularly pointed out in the appended claims.

30 My invention is illustrated in the accompanying drawings, forming part of this application, in which

Figure 1 is a vertical cross section through my device,

35 Figure 2 is a fragmentary elevation of my device, portions thereof being broken away,

40 Figures 3 and 3^a are front and side elevations, respectively, of the inner reciprocating valve,

45 Figures 4 and 4^a are front and side elevations, respectively, of the outer reciprocating valve,

50 Figures 5 and 5^a are front and side elevations, respectively, of the valve guide,

55 Figures 6 and 6^a are front and side elevations, respectively, of the outer valve oiling plate,

60 Figures 7 and 7^a are front and side elevations of the inner valve oiling plate,

65 Figure 8 is a diagrammatic view of my device showing the positions of the valves when the piston is on its intake stroke,

70 Figure 9 is a diagrammatic view of my device showing the positions of the valves when the piston is on its compression stroke,

75 Figure 10 is a diagrammatic view of my device showing the positions of the valves when the piston is on its firing stroke, and

80 Figure 11 is a diagrammatic view of my

device showing the positions of the valves when the piston is on its exhaust stroke.

In carrying out my invention, I provide an engine block 1 comprising a cylinder 2, an intake port 3, an exhaust port 4, a cylinder port 5, and a spark plug 6. The engine block 1 is provided with a valve compartment 7 which has a removable cover 8. A valve guide 9 divides the compartment 7 into two parts and is provided with an opening 9'.

An inner reciprocating valve 10 having an opening 11 therethrough is slidably disposed within the compartment 7 upon one side of the valve guide 9. An outer reciprocating valve 12 is provided with an intake passageway 13 and an exhaust passageway 14 which extend transversely therethrough. The outer reciprocating valve 12 is disposed within the compartment 7 upon the other side of the valve guide 9.

An outer valve oiling plate 15 is provided with openings 16 and 17 which are in alignment with the intake port 3 and the exhaust port 4, respectively. An inner valve oiling plate 18 is provided with an opening 19 which is in alignment with the cylinder port 5. The oiling plates 15 and 18 are provided with oil-receiving grooves 20 and 21, respectively, which are in communication with oil ducts, not shown.

A piston 22 is slidably disposed in the cylinder 2 and is operatively connected to the crank shaft 23 by means of a connecting rod 24. A relatively small gear 25 is keyed to the crank shaft 23 and is in mesh with a relatively large gear 26 which is keyed to an eccentric 27. Connecting arms 28 and 29 are pivotally mounted at their lower ends upon the eccentric 27 at spaced-apart points 30 and 31, respectively. The free end of the connecting arm 28 is pivotally secured to the inner valve 10 at the lower extremity thereof. In a like manner, the connecting arm 29 is pivotally secured to the outer valve 12 at the lower extremity thereof.

From the foregoing description of the various parts of the device, the operation thereof may be readily understood. In Figure 1, the piston 22 is halfway up on the exhaust stroke. Let us assume that the crank shaft 23 is rotated 180°. The gears 25 and 26 are of such ratio that the gear 26 will be rotated at one-half the speed at 100

which the gear 25 is rotated. Therefore, as the crank shaft 23 rotates 180° in a clockwise direction, the eccentric 27 will rotate 90° in a counter-clockwise direction. During this movement of the eccentric, the inner valve remains in approximately the same position, due to the fact that the pivot point 30 on the eccentric moves through an arc of 90° but to a point which is in horizontal alignment with its former position. The opening 11 in the inner valve therefore remains in alignment with the cylinder port 5. During this movement of the eccentric, the outer reciprocating valve 12 is moved upwardly bringing the intake opening 13 into alignment with the intake port 3 and into communication with the openings 9', 11, 19 and the cylinder port 5. This position is shown in Figure 8 where the piston 22 is on its intake stroke, thus drawing gases of combustion from the intake port 3 into the cylinder.

Attention is now called to Figure 9. Let us now assume that the crank shaft 23 has rotated an additional 180° . During this movement of the crank shaft, the eccentric 27 is rotated 90° moving the point 31 through an arc to a position which is in horizontal alignment with its former position, as shown in Figure 8. The outer valve 12 is therefore retained in its uppermost position. However, the point 30 has moved upwardly during this movement of the crank shaft, thus raising the inner valve to its uppermost position and closing the passageway from the intake port to the cylinder. The piston is now on its compression stroke.

Attention is now drawn to Figure 10 showing the crank shaft rotated an additional 180° and the eccentric rotated an additional 90° . During this movement of the eccentric, the outer valve is moved downwardly bringing the exhaust opening 14 into alignment with the exhaust port 4. The inner valve however retains its upper position, cutting off the communication between the exhaust port and the cylinder as the piston 22 moves downwardly in its firing stroke. Attention is now drawn to Figure 11 in which the crank shaft 23 has rotated an additional 180° and the eccentric 27 has rotated an additional 90° . During this movement of the eccentric, the outer valve 12 retains its lower position and the inner valve 10 is moved downwardly into its lowermost position, bringing the opening 11 into alignment with the cylinder port 5 and permitting the exhaust gases to be forced from the cylinder and through the exhaust port 4.

It is obvious that during the approximate-

ly horizontal movement of the points 30 and 31, the valves remain approximately stationary as the connecting arms 28 and 29 are swung. However, during the approximately vertical movement of the points 30 and 31, the valves 10 and 12 are rapidly raised and lowered.

I claim:

1. In a device of the type described, a cylinder having an opening therein, an intake port, an exhaust port, an outer reciprocating valve having an intake opening and an exhaust opening therein, an inner reciprocating valve having a passageway therethrough, a valve guide having a single passageway therethrough and positioned in alignment with the opening in said cylinder, and means for actuating said outer reciprocating valve for bringing said intake opening into and out of alignment with said intake port and passageway in said valve guide and for bringing said exhaust opening into and out of alignment with said exhaust port and the passageway in said valve guide, said means being adapted to move said inner valve for bringing the passageway therein into and out of communication with the opening in said cylinder and the opening in said valve guide.

2. In a device of the type described, a cylinder having an opening therein, an intake port, an exhaust port, an outer reciprocating valve having an intake opening and an exhaust opening therein, an outer valve oiling plate having an intake passageway disposed in communication with said intake port and an exhaust passageway disposed in communication with said exhaust port, an inner reciprocating valve having a passageway therethrough, an inner valve oiling plate having a passageway in communication with the opening in said cylinder, a valve guide having a single passageway therethrough and positioned in alignment with the opening in said cylinder, and means for actuating said outer reciprocating valve for bringing said intake opening into and out of alignment with said intake port, said intake passageway, and the passageway in said valve guide, and for bringing said exhaust opening into and out of alignment with said exhaust port, said exhaust passageway, and the passageway in said valve guide, said means being adapted to move said inner valve for bringing the passageway therein into and out of communication with the opening in said cylinder, the passageway in said inner valve oiling plate, and the opening in said valve guide.

GARLAND H. ROOSE.
